UNITED STATES PATENT OFFICE.

JOHN B. JOVINO, OF BROOKLYN, NEW YORK.

SAFETY HOLSTER.

Application filed August 7, 1925. Serial No. 48,721.

This invention relates to holsters for revolvers and similar fire-arms and particularly to the provision of what is known as a safety holster wherein the revolver is locked 5 against accidental displacement from the holster when inserted thereinto, and the object of the invention is to provide a holster of the class specified with improved means for automatically locking and retaining a 10 revolver within the holster and with means actuated by the hand to withdraw the revolver, and in the operation of withdrawing the revolver for releasing the locking means to permit the free and easy removal of the 15 revolver; a still further object being to provide a holster of the class specified, the locking means of which is of such construction and operation as to be fool-proof in use and prevent the accidental discharge of the 20 revolver in the operation of removing the same from the holster as has been experienced with other devices of this class; a still further object being to provide locking means which will prevent the withdrawal 25 of the revolver from the holster without the actuation of the locking means to move the same into inoperative position; and with these and other objects in view the invention consists in a device of the class and for the 30 purpose specified which is simple in construction and operation and efficient in use and which is constructed as hereinafter described and claimed.

The invention is fully disclosed in the following specification, of which the accompanying drawing forms a part, in which the separate parts of my improvement are designated by suitable reference characters in each of the views, and in which:—

Fig. 1 is a side view of the holster showing a revolver mounted therein;

Fig. 2 is a section on the line 2—2 of Fig. 1; and,

Fig. 3 is a section on the line 3—3 of Fig. 1 and on an enlarged scale.

In practice, I provide a holster 5 of the general form of holsters, as usually constructed, and comprises a barrel portion 6 into which the barrel of the revolver is insertable, the barrel portion 6 being closed at its contracted end as seen at 7 and being composed of a single piece of leather folded or curved along the straight side edge 8 of the holster and the edges of which are brought together and stitched as seen at 9, the stitching extending through the closed end 7. The

holster thus described comprises a front wall 10 and back wall 11, the front wall being shorter than the back wall and the upper edge of which is curved in the manner seen at 12 to expose the butt 13 of a revolver 14 through the open end of the holster, the back wall 11 lying in parallelism with the longitudinal plane of the butt 13, as clearly seen in Fig. 1 of the drawing.

Mounted upon the inner face of the back wall 11 is a supplemental wall 11^a which extends into the chamber of the holster to a point adjacent the barrel of the revolver when inserted into the holster, and as seen in Fig. 2 of the drawing a projecting tongue 11^b is formed on the supplemental wall 11^a, which extends transversely of the holster and against which the trigger loop or guard 15 of the revolver is adapted to abut.

At 16 I have shown my improved lock or catch device which, in the construction shown, is substantially yoke-shaped in form and comprises a strip of metal 17 one end portion of which is positioned between the back wall 11 and supplemental back wall 11^a, and is riveted or otherwise secured to the supplemental back wall as seen at 18 in Fig. 2 of the drawing, the cross head 19 of said strip extending beneath the tongue 11^b and the other end 20 of said strip extends in parallelism with the front wall 10 of the holster, and on the inner face thereof. A supplemental strip 21 is secured to the free end of the end portion 20 of the strip 17 and extends in parallelism and in spaced relation to said end portion and is anchored in the cross head 19, the supplemental strip 21 being provided centrally of the side portions thereof with ears 22 supporting a hinge pin 23 which passes through corresponding ears 24 on a spring catch arm 25, the resiliency of said arm by its engagement with the end 20 of the strip 17 serves to normally project the catch nose 26 thereof through an aperture 27 formed in the supplemental plate 21 adjacent the cross head 19, see Figs. 1 and 2 of the drawing, and the other end portion of the catch arm is provided with a knob or button 28 which projects through an aperture in the end portion 20 of the strip 17 and through an aperture formed in the front wall 10, said apertures being sufficient to receive the shank of the button only. The end portion 20, including the supplemental strip 21, is enclosed by a comparatively thin casting 29, which is stitched to the front wall of

the holster on the line of stitching 30, and the projecting tongue 11^b also forms an enclosure for the cross head 19 as will be apparent.

5 The entire holster proper is composed of heavy leather or other suitable material, while the casing 29 is composed of finer leather or other material and is employed solely for the purpose of forming a neat and 10 finished appearance within the holster and to protect the catch or lock device from the weather, and to prevent the revolver from coming in contact with the metallic parts of the catch device except for the catch nose 26.

15 With my improved construction it will be understood that the yoke-shaped strip 17 will be composed of supplemental heavy spring-like metal of sufficient stiffness to hold that part of the holster, in connection 20 with which it is mounted, in fixed or substantially fixed position, and the spring or resilient properties of said strip are such as to place the revolver under slight friction when inserted into the holster but not sufficient 25 to prevent the automatic locking of the revolver in the holster when dropping the same thereinto. However, it will be apparent that slight pressure may be applied to insure the locking of the revolver in the 30 holster. When the revolver is mounted in position the projecting catch nose 26 engages the trigger loop 15, or the lower wall thereof, as seen in Figs. 1 and 2 of the drawing, and prevents the accidental displacement of 35 the holster and further prevents the withdrawal of the holster until the button 28, which is exposed through the front wall 10 of the holster, has been depressed, but upon moving the button 28 inwardly by the index 40 finger of the hand in the operation of withdrawing the revolver by grasping the butt end thereof, the catch nose 26 is moved into inoperative position and the revolver may be readily withdrawn from the holster. The 45 pressure upon the button by the finger of the hand may be applied from the tip of the finger or by drawing the finger lengthwise over the button and applying slight inward pressure.

50 It will also be noted that the button 28 is so positioned on the holster that in the removal of the revolver by pressure applied to the button with the index finger of the hand, when the revolver has been withdrawn from 55 the holster, said index finger or trigger finger will lie in readiness upon the trigger loop 15 permitting the quick insertion of the finger into such loop for engagement with the trigger affording a quick discharge of the 60 revolver, if desired and necessary, yet it is to be noted that the pressure applied to the button for releasing the catch, to permit the removal of the revolver, cannot in any way cause an accidental discharge of the revolver or an operation of the trigger in that the

trigger loop and trigger are normally contained within the holster and protected by the front and back walls thereof while the revolver is removed.

It will be understood that while I have 70 shown one form of construction for carrying my invention into effect and one method of mounting the same in connection with a holster, that I am not necessarily limited to the details of construction herein shown and 75 described, or the method of their mounting, and various other changes in and modifications of the construction herein shown and described may be made, within the scope of the appended claims, without departing from 80 the spirit of my invention or sacrificing its advantages.

Having fully described my invention, what I claim as new and desire to secure by Letters Patent, is:—

85 1. A catch device for use in connection with revolver holsters comprising a U-shaped body of spring metal adapted to encircle the trigger guard portion of a revolver placed in the holster, a catch device movably mounted in said body and adapted to engage a predetermined part of a revolver inserted in the holster to prevent its displacement, a part projecting through the holster for moving said catch device into inoperative position, and said body being closed in a casing or jacket constituting part of the holster.

90 2. A holster of the class described comprising a barrel portion and a trigger guard receiving portion, a catch device for preventing the accidental displacement of a fire-arm inserted into the holster, said catch device being mounted in the trigger guard receiving portion of the holster and encircling and enclosing the trigger guard of a fire-arm placed in the holster, and means on 95 said catch device for engaging the fire-arm to prevent its removal from the holster.

100 3. A holster of the class described comprising a barrel portion and a trigger guard receiving portion, a catch device for preventing the accidental displacement of a fire-arm inserted into the holster, said catch device being mounted in the trigger guard receiving portion of the holster and encircling and enclosing the trigger guard of a fire-arm placed in the holster, means on 105 said catch device for engaging the fire-arm to prevent its removal from the holster, and means exposed through the holster for moving said last named means into inoperative position to release the fire-arm.

110 4. A holster comprising a barrel portion having front and back walls, the top of the holster being open to permit the insertion of the barrel, cylinder and trigger guard portions of a fire-arm thereinto and to conceal the same therewithin, and means mounted in the trigger guard portion of the hol- 115

ster for engaging the trigger guard of the fire-arm to prevent the accidental displacement thereof.

5. A holster comprising a barrel portion having front and back walls, the top of the holster being open to permit the insertion of the barrel, cylinder and trigger guard portions of a fire-arm thereinto and to conceal the same therewithin, means mounted in the trigger guard portion of the holster for engaging the trigger guard of the fire-arm to prevent the accidental displacement thereof, and means exposed through the front wall of the holster for moving said first named means into inoperative position.

6. A catch device for use in connection with revolver holsters comprising a U-shaped body of spring metal mounted in the holster and adapted to encircle the trigger guard of a revolver placed in the holster, and a catch

device movably mounted in said body and adapted to engage a predetermined part of a revolver inserted in the holster to prevent its displacement.

7. A catch device for use in connection with revolver holsters comprising a U-shaped body of spring metal mounted in the holster and adapted to encircle the trigger guard of a revolver placed in the holster, a catch device movably mounted in said body and adapted to engage a predetermined part of a revolver inserted in the holster to prevent its displacement, and a part projecting through the holster for moving said catch device into inoperative position.

In testimony that I claim the foregoing as my invention I have signed my name this 1st day of August, 1925.

JOHN B. JOVINO.
